UNITED STATES PATENT OFFICE.

DANTE SOLON CURTISS, OF SEATTLE, WASHINGTON.

CHAIR ATTACHMENT.

No. 918,787.

Specification of Letters Patent.

Patented April 20, 1909.

Application filed February 12, 1908. Serial No. 415,467.

To all whom it may concern:

Be it known that I, DANTE S. CURTISS, a citizen of the United States, and a resident of Seattle, in the county of King and State of Washington, have invented a new and Improved Chair Attachment, of which the following is a full, clear, and exact description.

The invention relates to furniture, and its object is to provide a new and improved rocking attachment and foot rest for use on ordinary chairs and rocking chairs, and arranged to permit the user to conveniently tilt the chair back to a desired position, thus insuring comfort to the occupant of the chair.

15 The invention consists of novel features and parts and combinations of the same, which will be more fully described hereinafter and then pointed out in the claims.

A practical embodiment of the invention 20 is represented in the accompanying drawings forming a part of this specification, in which similar characters of reference indicate corresponding parts in all the views.

Figure 1 is a perspective view of the improvement as applied to a rocking chair; Fig. 2 is a sectional side elevation of the same; Fig. 3 is an enlarged cross section of one of the pivot clips as applied to a runner of the rocking chair, and Fig. 4 is a perspective view of part of the attachment.

To the rockers A of the rocking chair B are secured the transversely-extending clips C by the use of set screws D, screwing in the inner ends of the clips C against a block E of wood 35 or other material resting against the inner face of the corresponding rocker A. The set screws D of the two clips C form pivots for the arms F of an auxiliary rocker to swing on, the said arms F being provided at their rear ends with 40 eyes F' loosely engaging the set screws D, between the inner ends of the clips and the blocks E, as plainly indicated in Fig. 3. The outer ends of the arms F of the rocker are connected with each other by a cross bar F², 45 forming a foot rest for the feet of the occupant of the chair. Springs H connect the arms F of the auxiliary rocker with the forward legs B' of the rocking chair B, so as to normally hold the auxiliary rocker in an upward or a folded position.

An extension foot rest G is provided with side arms G' formed at their rear ends into coils G² through which extends the cross bar F², to allow the extension foot rest G to swing 55 on the cross bar F² forming the main foot rest. The coils G² terminate in arms G³ rest-

ing against stop pins F³ secured to the rocker arms F, so as to hold the extension foot rest G in proper position forward of the main foot rest, as will be readily understood by reference to the drawings. Now when the device is attached to the chair as shown and described, and the operator places his feet on the cross bar F² and bears down on the same, then the rocker arms F resting on the floor 60 cause a backward tilting of the rocking chair B on its rockers A until the desired position is reached. The feet of the occupant of the chair in bearing down on the cross bar F² finally bring the toes in contact with the extension foot rest G, so that the legs of the occupant come to perfect repose, to increase the comfort of the occupant of the chair.

Although I have shown and described the device as applied to a rocking chair, it is evident that same may be attached to an ordinary chair, dining room chair and the like, to tilt the chair backward to a desired angle and to provide a convenient foot rest for the occupant's feet.

The chair attachment is very simple and durable in construction, can be readily applied to the chair or removed therefrom whenever it is desired to do so.

Having thus described my invention, I 85 claim as new and desire to secure by Letters Patent:

1. A chair attachment comprising transverse pivots for attachment to the chair, and a pair of rockers connected with each other 90 at their forward ends by a cross bar forming a foot rest, the rockers being fulcrumed at their rear ends on the said pivots and contacting with the floor in advance of the pivots.

2. A rocking attachment for chairs comprising a pair of rockers connected together at their forward ends by a cross bar forming a foot rest, means for pivotally connecting the rear ends of the rockers with a chair, 100 whereby they may contact with the floor in advance of their pivots, and an extension foot rest fulcrumed on the cross bar of the rockers.

3. A chair attachment comprising transverse pivots for attachment to the chair, rockers connected with each other at their forward ends by a cross bar forming a foot rest and provided with stop pins adjacent to the cross bar, the rocker arms being fulcrumed at their rear ends on the said pivots, and contacting with the floor in advance of

the pivots, and an extension foot rest having eyes engaging the said cross bar and arms engaging stop pins on the said rockers.

4. A chair attachment comprising a pair 5 of pivot clamps having set screws for attaching the clamps to the chair, rocker arms rigidly connected with each other at their forward ends by a cross bar forming a foot rest, the rear ends of the said rocker arms terminating in eyes loosely engaging the said set 10 screws for the rocker arms to swing on.

5. A chair attachment comprising a pair 15 of pivot clamps having set screws for attaching the clamps to the chair, rocker arms rigidly connected with each other at their forward ends by a cross bar forming a foot rest, the rear ends of the said rocker arms terminating in eyes loosely engaging the said set screws for the rocker arms to swing on.

ward ends by a cross bar forming a foot rest, the rear ends of the said rocker arms terminating in eyes loosely engaging the said set screws for the rocker arms to swing on, and springs connecting the rocker arms with the 20 chair to hold up the rocker arms and foot rest when not in use.

In testimony whereof I have signed my name to this specification in the presence of two subscribing witnesses.

DANTE SOLON CURTISS.
